GENEVIEVE HOUGHTON, OF NEW YORK, N. Y., ASSIGNOR TO SAMUEL STERNBERGER,
OF PHILADELPHIA, PENNSYLVANIA.

SAFETY-PIN.

1,000,650.

Specification of Letters Patent. Patented June 9, 1914.

Application filed July 24, 1913. Serial No. 780,907.

To all whom it may concern:

Be it known that I, GENEVIEVE Houghton, a citizen of the United States, residing in the city, county, and State of New York, have invented a new and useful Safety-Pin, of which the following is a specification.

My invention consists in providing the guard or shield of a safety pin with means for locking the pin point when in operative position, so as to prevent accidental displacement of said point from said guard or shield, the construction and operation of said means being hereinafter set forth.

The invention is satisfactorily illustrated in the accompanying drawing, but the important instrumentalities thereof may be varied, and so it is to be understood that the invention is not limited to the specific arrangement and organization shown and described.

Figure 1 represents a side elevation of a safety pin embodying my invention. Fig. 2 represents a longitudinal section of a portion thereof. Fig. 3 represents a transverse section on line $\alpha-\alpha$, Fig. 1. Fig. 4 represents a plan view of a detached portion.

Similar numerals of reference indicate corresponding parts in the figures.

Referring to the drawings: 1 designates the pin proper of a safety or shield pin, 2, the point portion thereof, and 3 the member with which said pin proper is connected by the intermediate coil 4 and which is fixed to the clamp member 5 of the shield or guard 6, with which latter the point portion 2 of the pin proper enters as its seat, all of said parts, separately considered, being well known.

On the side of the point member at opposite places are the grooves 7 which extend in a direction thereon parallel with the side plates 8 of the shield or guard 6, said side plates being somewhat resilient in lateral direction, and in said plates are tongue-shaped internal projections 9 which are turned or swaged-in from said walls and taper inwardly toward each other, from what may be termed the bases of said plates a certain distance and then turn laterally outward to the back or the top-connecting bend 10 thereof, so as to be wedge-shape or converging, the greatest depths of which are above, taken in the direction of the figure of the drawings, the upper terminals

of said tongue-shaped projections forming well-defined shoulders 11 opposite to each other, just below the bend 10, it being noticed that said tongues are in the paths of the grooves 7 of the pin point portion 2, so that in the use of the safety pin when said pin point is inserted in the shield or guard 8 the grooves 7 of said point portion receive the lower ends or points of the tongue-shaped projections 9, thus guiding said grooves on the latter. Then the walls of said grooves 7 ride on said tongue-shaped projections and as the latter gradually approach each other at the top, said walls force apart the side plates of the shield or guard until said walls clear the shoulders 11 when the side plates spring together placing the pin point portion that is below the walls of said grooves upon said shoulders and holding the pin proper firmly locked in the shield or guard 6 and preventing the accidental displacement thereof, until when the safety pin is to be opened, the pin point portion is moved in a direction toward its entrance, when said portion 80 owing to the superior force exerted thereagainst it, first presses the shoulders 11 and rides over the same placing the walls of the grooves 7 on the tongue-shaped projections 9 thus again spreading-apart the side plates 8 of the shield or guard and allowing the walls of the grooves 7 to ride down said tongue-shaped projections until the latter are cleared the side plates then resuming their normal condition and the pin 90 point portion emerging from the shield or guard, whereby the device is opened and may be disconnected from the article or garment to which it has been applied.

When the pin is in locked position, the shoulders 11 afford lengthened supports for the same, and so resist in any direction the unlocking of the point portion until properly overcome in the manner stated, or should it have been bent.

Having thus described my invention what I claim as new and desire to secure by Letters Patent, is:—

1. In a safety pin, a pin proper having in the side of its point portion a groove, and a pin point shield embodying two side plates and a back joining the same and having on a side plate a tongue-shaped internal projection which flares from the base of said plate to the back of the shield and

2
is wedge-shaped toward the opposite side, there being a shoulder extending to the side of the back of the shield for receiving the under side of the pin point to support and 5 lock the same.

2. In a safety pin, a pin proper having its point portion provided with a groove in the side thereof, and a shield for the pin point comprising two side plates and a 10 back joining the same and having on a side plate a tongue-shaped internal projection which is adapted to receive freely said groove, said projection being wedge shaped from the base of said plate toward 15 the back of the shield, and forming with said wall adjacent to said back an inwardly projecting shoulder which extends to the side of said back and on which the under side of said pin point portion is adapted 20 to be seated and locked.

3. In a safety pin, a pin proper having its point portion provided with recesses in the side at opposite places thereof, and a shield for the pin point comprising two 25 side plates and a back joining the same and having on its side plates inturned tongue-shaped internal projections which flare from the base of said plates toward the back of the shield and are wedge shaped toward

each other and shoulders at the inner terminals of said tongue-shaped internal projections, said shoulders extending laterally outwardly from said inner terminals to the sides of said bend of the shield and being adapted in the closed position of the 35 pin to have the portion of the latter below the walls of said grooves seated thereon.

4. In a safety pin, a pin proper having its point portion provided with grooves in opposite sides thereof and a shield having 40 side plates and a bend and tongue-shaped projections on said plates, said projections being indented and extending inwardly toward each other from the bases of said plates to the bend thereof, the upper terminals of said tongues forming shoulders disposed opposite each other and extending laterally outwardly from said terminals to the sides of the bend of the shield and adapted to engage the walls 45 of said grooves and adapted to support and lock the point portion of the pin.

To the above I have signed my name.
